UNITED STATES PATENT OFFICE

WILLIAM C. PEASE, OF THE DALLES, OREGON

SHOE-DISPLAY RACK

Application filed January 6, 1928. Serial No. 245,007.

This invention relates to display racks for shoes and is particularly adapted for stores.

The primary object of my invention is the provision of an improved shoe rack.

5 Another object of my invention is the provision of an improved shoe rack which will display practically all of many pairs of shoes, the supporting part of the rack being subordinated to the display of the shoes themselves.

Another object of this invention is the provision of an improved shoe rack having provision for supporting the shoes in an upright position, the toes being lower than the heels, 15 the angles of the plane of support of the shoe to the horizontal being about 11°.

Another and still further object of my invention is the provision of an improved shoe rack which may stand in the middle of a floor 20 and have shoes on both sides of its structure, the view of the shoes being practically unobstructed in any direction.

Another and still further object of my invention is the provision of an improved shoe rack having a readily detachable shoe stand.

Another and still further object of my invention is the provision of an improved shoe rack having an adjustable shoe heel holder.

Other and further objects of my invention 30 will be apparent to those skilled in the art from a reading of the complete specification and claims.

Referring to the drawing wherein I have 35 illustrated an embodiment of my invention,

Fig. 1 is a front elevation of my invention, in one form.

Fig. 2 is a top plan view of Fig. 1.

Fig. 3 is an end elevational view.

40 Fig. 4 is a side elevation of another form of my invention.

Fig. 5 is a top plan view of the structure shown in Fig. 4.

Fig. 6 is a cross section on line 6—6 of

45 Fig. 1.

Figs. 7 and 8 are detail views of the readily detachable means for holding the stands in place, the latter being a sectional view on the line 8—8 of Fig. 7.

50 Fig. 9 is a view of a portion of the stand

14^a showing the improved heel holding device in operative position.

Fig. 10 is a perspective view of the parts constituting the heel holding device showing the same in position ready to be assembled. 55

Fig. 11 is a fragmental view showing one method of applying a size tag to the shoe stand.

In Figures 1, 2 and 3, the numerals 10 designate floor pieces which, with the uprights 11 and the braces 12, form the supports. 60

Between the supports are provided longitudinal members 13 which are supported by the supports 10, 11, 12 and in turn carry the paddles or, stands 14^a, 14^b. These longitudinal members 13 are arranged one above the other. It will be noted that a row of paddles or, stands, in the form shown in Fig. 1, 65 extends, from each longitudinal member 13, in each direction, that is, forward and backward, as viewed in Fig. 1. The form of the paddle stand 14^a, 14^b may vary, the form 14^b being of a size to receive a pair of shoes. It is also to be understood that different sizes 70 may be provided for men's, women's and children's shoes. 75

From the showing of Fig. 3, it will be clear that the sides of the shoes on the ends of the rows may be clearly seen, including the sides of the heel, for the reason that the supports are so constructed as to have the upright portion to the rear of the shoe supporting portion. 80

Another important feature of my invention is the provision of a readily detachable means for the stands whereby the same racks may be used at will, for men's, women's, and children's shoes, it being merely necessary to remove a stand of one size and replace it with another of another size. In this way a rack may be used for men's, women's, and children's shoes and the relative numbers of the different types, changed whenever desired. 85

In order to bring about this result and to make it possible for any clerk or salesman to make these changes without disturbing the rack as a whole, and without tools, I provide a holding means of which an embodiment is illustrated in Figs. 7 and 8. The details of 90 95 100

this construction are omitted from Figs. 1 to 5 as these details would not show on the small scale.

To the bottom of the paddle stand 14^b, I 5 secure a suitable spring member 15 by suitable screws 16, 17. The portions 15^a, 15^b are so arranged and shaped that they will receive a head of a screw 18 which has previously been embedded in the longitudinal member 13. It will be seen that the paddle stand 14^b may be readily removed by merely moving rearwardly to the dotted position shown 10 in Fig. 7. The attaching operation may be made in the same but reverse way, first placing the paddle stand 14^b in the dotted position of Fig. 7 and then drawing forward. The spring members 15 have resiliency sufficient to hold the paddle stand 14^b in the desired adjusted position. For attaching single 15 shoe stands 14^a, a single member 15 may be used, if desired. In addition to the readily changeable feature, this detachable stand has advantages in shipping. A smaller crate or box may be used than could be used if the 20 paddles or, stands 14^a, 14^b were permanently secured in place.

In Figs. 4 and 5, I have shown a modification intended to occupy a smaller space than the rack shown in Figs. 1 to 3.

30 In this device, the parts 10', 11', and 12' correspond to the parts 10, 11 and 12 already described. In order to hold the paddles or, stands 14^a, 14^b in position relative to the part 11', I provide longitudinal members 13' which preferably extend slightly beyond the sides of the part 11' in order to provide fastening space for either the paddle stand 14^a or 14^b, depending upon the taste of the user. The fastening means 15, 16, 17, 18 may be used equally with this type, it being only necessary to proportion the parts to allow sufficient space between the rear and the paddle stand 14^a or 14^b, to allow the rearward movement necessary to disengage the member 15 from the screw head 18.

45 I have shown the stands on this form shown in Figs. 4 and 5 in staggered relation as to height. This method assists in the display of the sides of the shoes which is one of the important aims of this invention.

50 On the ends of the racks illustrated in Figs. 1 to 3, I have provided stands which are secured, in place, to the member 11 in a manner just described for Figures 4 and 5.

55 In order to provide a means for securing the heels of the shoes in a particular position, I provide an adjusting means which may be adjusted for different sizes of heels and also for different desired positions of the heel laterally of the stand.

60 On Fig. 9 I have shown a perspective view of the assembled parts of the heel holding device and on Fig. 10 the parts are shown in relative position ready for assembling. The angle piece 20 has two screw holes by which

it is secured to the paddle stand, as 14^a, at the proper position. Two complementary parts 21, 22 are then secured in place, through openings 21^a, 22^a, by the adjusting screw 23. A nut 24 completes the structure. By tightening of the nut 24 when the right and left complementary holding members 21, 22 are in place, the wings 21^b, 22^b will hold the heel of the shoe on display, at the desired place. This feature is desirable since it assists in the return of the shoe to its proper lateral and longitudinal position when removed, thereby retaining the "dress" appearance of the rack as a whole. The openings 21^a, 22^a are elongated to provide a wide range of adjustment.

70 This shoe rack with its many advantages has been found to have a very high value as a display article. Its open structure displaying the shoes without obstruction of the rack gives the feeling to the prospective customer of the absence of any support, the shoes being apparently standing by themselves.

75 While the device shown in Figs. 9 and 10 has not been shown in detail in each instance of the showing of paddles or, stands 14^a, 14^b, 80 it is to be understood it may be used throughout the structure.

85 I have found that the best angle to display shoes in the upright position on my rack is substantially 11° to the horizontal. I have 90 therefore so shown the paddles or, stands 14^a, 14^b.

95 Part of the shoe rack might be made of metal or all of metal or wood or some other suitable material.

100 While I have shown and illustrated embodiments of my invention, I desire to have it understood that the drawing is merely illustrative and that modifications and changes may be made without departing from the spirit of my invention and within the scope of the appended claims.

105 Having described my invention, what I claim and desire to secure by Letters Patent is:—

110 1. A shoe rack comprising a plurality of superimposed rows of upwardly inclined paddles for holding shoes in upright position, and means on said rack for supporting the paddles at the rear ends thereof, said means being substantially all to the rear of the heels of the shoes when being displayed on the paddles whereby a view of the sides of the shoes of one row is unobstructed by the rack structure of the row above.

115 2. A shoe rack comprising a plurality of superimposed rows of upwardly inclined paddles for holding shoes in upright position, each paddle being of a width to receive a pair of shoes and means including a 120 bar for each row for supporting the paddles at the rear ends thereof, said means being substantially all to the rear of the heels of the shoes when being displayed on the paddles, whereby a view of the sides of the shoes 125

of one row is unobstructed by the rack structure of the row above.

3. A shoe rack comprising a plurality of superimposed rows of upwardly inclined paddles for holding shoes in upright position, means including a bar for each row for supporting the paddles, said means being substantially to the rear of the heels of the shoes when being displayed on the paddles 10 whereby a view of the sides of the shoes on each row is unobstructed by the rack structure of the row above, there being stands extending from the supports at substantially 90° from each other, horizontally.

15 4. A shoe rack comprising a plurality of upright supporting means, superimposed horizontally-extending bars, each supported at both ends by the supporting means, upwardly inclined paddles for carrying shoes in 20 an upright position and attached at their rear ends to the bars, the supporting means and bars being substantially all at the rear of the positions occupied by the shoes whereby a view of the sides of the shoes is unobstructed 25 by the rack structure.

5. A shoe rack comprising upright supporting means, end-supported superimposed horizontally-extending bars, upwardly inclined shoe supporting paddles for supporting 30 shoes in upright position and secured to and supported at their rear ends by the bars, the supporting means being substantially all to the rear of the positions occupied by the 35 shoes when placed in place on the shoe paddles, the shoe paddles being readily detachable from the bars without the use of tools.

6. A shoe rack comprising upright supporting means, end-supported superimposed horizontally-extending bars, upwardly inclined shoe supporting paddles for supporting 40 shoes in upright position, the said paddles being secured to and supported at their rear ends to said bars, the supporting means being substantially all to the rear of the positions occupied by the 45 shoes when placed in place on the shoe paddles, the shoe paddles being readily detachable from the bars by relative movement therebetween, without the use of tools.

50 7. A shoe rack comprising upright supporting means, end-supported superimposed horizontally-extending bars, upwardly inclined shoe supporting paddles for supporting 55 shoes in upright position and secured to and supported at their rear ends by the bars, the supporting means being substantially all to the rear of the positions occupied by the 60 shoes when placed in place on the shoe paddles, and an adjustable heel-holding device on the paddles to receive and hold heels of varying widths.

In testimony whereof I hereto affix my signature.

WILLIAM C. PEASE.
